UNITED STATES PATENT OFFICE.

LESLIE S. WILDER, OF SPRINGFIELD, MASSACHUSETTS.

ELECTRIC TEMPERATURE-INDICATOR.

SPECIFICATION forming part of Letters Patent No. 660,352, dated October 23, 1900.

Application filed February 17, 1900. Serial No. 5,563. (No model.)

To all whom it may concern:

Be it known that I, LESLIE S. WILDER, a citizen of the United States of America, and a resident of Springfield, in the county of 5 Hampden and State of Massachusetts, have invented certain new and useful Improvements in Electric Temperature-Indicators, of which the following is a full, clear, and exact description.

10 This invention relates to improvements in temperature-indicators of the class in which a thermostat affected by the temperature conditions closes a normally-open electric circuit and thereby insures the operation of an 15 alarm device or audible or other description of indicator which is connected in electric circuit and operating by the current established therethrough.

The present device is especially designed 20 for use in hospitals, the audible indicator sounding upon the rising of the temperature a few degrees above the normal or falling therebelow.

The purposes of this invention are to produce 25 a simple, practical, and efficient indicator of the general class indicated, and, furthermore, to produce one which is most readily adaptable or adjustable, so as to be operative to sound the indicator within any desired 30 range of temperature change, and which, moreover, is compact and self-contained and portable, so that the apparatus entire may be placed anywhere desired in the room or suitably remote therefrom, as occasion may render 35 desirable.

The invention consists in the combination or arrangement of devices and the construction thereof, all substantially as hereinafter described, and set forth in the claim.

40 Reference is to be had to the accompanying drawings, in which—

Figure 1 is a plan view of the temperature-indicator, certain parts being broken away for the disclosure of underlying parts for the 45 purposes of clearer illustration. Fig. 2 is a vertical longitudinal section taken on the line 2 2, Fig. 1.

In the drawings, A represents a support on which is screwed the brass or other metallic 50 plate B. The said support A may advantageously be made of wood, and, as shown, constitutes the cover of a box or cabinet A². At

one end of the plate B is riveted or otherwise secured the extremity of a U-shaped metallic part C, screwed or riveted on the upper 55 approximately horizontally extending free end of which is the thermostat-bar D. This bar is composed, as common in this class of appliances, of two or more materials, those shown being a thin metallic strip of metal a 60 and a superimposed thickness of hard rubber or gutta-percha b. These materials are united in any suitable manner, rivets d d being shown. At the opposite end of the base-plate B from the U-shaped rising part 65 C is a riser or upright E, the extremity of which, as indicated at f, is of U shape, between the separated members of which the extended end portion of the metallic layer a of the thermostat-bar is extended. The 70 base of the upright E is by the layer g of suitable material insulated from the base, and consequently from the part C in metallic connection with the base and on which part the thermostat-bar is mounted. Through the opposite portion of the U-shaped extremity of the upright E screw the threaded contacts h and h², the approached ends of which may be comparatively close to the normal position of the extremity of a or considerably distant 75 therefrom. The screw i has its shank passed loosely through the thermostat-bar and through the hole i² therefor in the U-shaped part C and passes with a screw engagement into the base-support thereunder, the head of 80 this screw overlying and engaging the top of the thermostat-bar. By turning the screw the bar as a whole may be adjusted, and this capability of adjustment, together with the adjustable contacts h and h² at the opposite end 85 of the apparatus, renders the same adaptable 90 with great nicety to fulfil the purposes for which it is intended under all circumstances.

G represents a battery.

m and n represent binding-posts.

H represents a switch having the contact j and the movable or switching contact j².

J represents an audible electric indicator or "buzzer" which in itself comprises no novelty, the same embodying electromagnet and 100 armature and a spring make-and-break device, as common.

From one pole of the battery the wire 10 runs to the binding-post 12, which is in elec-

trical connection with the electromagnet. From another binding-post 13, which is also in electrical connection with the electromagnet, the wire 14 runs to connection with the 5 movable switch member j^2 , and from the contact j (closed onto which the switch member may be moved) the wire 14^a extends to connection with the binding-post n , and from this latter binding-post the wire 15 extends to connect with the metallic base f^2 of the upright or riser E. From the binding-post m , which is on the same plate or metallic base B as the binding-post n , an electric wire 16 extends to connection with the other pole of the battery 15 G. When the switch is closed, parts j^2 and j rendering the wires 14 and 14^a continuous, and temperature changes above or below the normal are such as to cause the deflection of the thermostat-bar, so that the metallic portion a thereof is in contact with either of the contact-screws h or h^2 , the current from the battery will by the circuit then closed pass from wire 16 to binding-post m , across the metallic base, to and through the U-shaped upright 20 C, thence along the metallic strip a to and through the upright E, with which wire 15 is connected, and through said wire to the binding-post n , thence by wire 14^a through the closed switch and wire 14, to and through the 25 electromagnet of the circuit-making-and-breaking buzzer, and back by wire 10 from the latter to the battery.

I make no claim to the construction of the audible electrically-actuated indicator, and 30 in place thereof, manifestly, the most common form of alarm-bell might be employed.

When the apparatus is desired to be inactive, as on an occasion when no alarm in the apartment is desired, the switch may be left 35 open, as indicated in Fig. 1, whereby no tem-

perature changes will result in closing the circuit, and consequently the battery will not become run down or exhausted.

It is very convenient and satisfactory to have the battery G or a series of batteries, 40 properly connected, inclosed in the box or cabinet A², on the cover of which the principal parts of the apparatus which have been described at length are mounted.

Having thus described my invention, what 45 I claim, and desire to secure by Letters Patent, is—

In an electric temperature-indicator, in combination, the metallic base-plate B having a U shape as shown, a thermostat-bar D, the 50 extremity of which rests on the top member of said support C, the screw i passing through the thermostat-bar and loosely through the top member of the support and with a screw engagement into the bottom member, the upright or riser having the base thereof supported by, but insulated from, the base-plate B, and having the U-shaped extremity f provided with the adjustable contact-screws h and h^2 threading through opposite portions of 55 said part f , and between the ends of which the extremity of the thermostat-bar is extended, circuit connections normally open and adapted to be closed by the movement of the bar against one of said contact-screws, having 60 connected therein a battery and an electromagnetic audible signaling device, substantially as described.

Signed by me at Springfield, Massachusetts, this 13th day of December, 1899.

LESLIE S. WILDER.
